Patented Dec. 5, 1922.

FIG. 1. FIG. 2. FIG. 3.

Inventor

L. Bordwell

By A. S. Pattison

Attorney

UNITED STATES PATENT OFFICE.

LAVERN BORDWELL, OF NEW YORK, N. Y.

BEATER.

Application filed August 4, 1919. Serial No. 315,087.

To all whom it may concern:

Be it known that I, LAVERN BORDWELL, a citizen of the United States, residing at New York city, in the county of New York and State of New York, have invented certain new and useful Improvements in Beaters, of which the following is a specification, reference being had therein to the accompanying drawing.

10 This invention relates to improvements in beaters, and is particularly adapted for culinary use, and pertains to that type of beaters shown in Patent No. 892,856, July 7th, 1908, granted to E. W. Ladd.

15 My present invention relates to an improvement in the handle of the beater, and the objects of the improvement are to make the frame more rigid; to provide the greatest strength therefor where it is required; to 30 enable the handle to be shaped to meet individual needs without impairing the strength; capable of being shaped to suit the natural grasp of the user; ease and reduction of cost in manufacture.

25 In the accompanying drawings—

Figure 1 is a side elevation of the upper end of the beater mechanism, showing my improvement applied thereto with the handle shaped to suit certain requirements of 30 the user.

Figure 2 is an edge elevation of Fig. 1, shown partly in section.

Figure 3 is a side elevation showing the improved handle shaped to suit other requirements of the user.

40 This invention relates to a beater having a frame 1 to which is journaled an operating wheel 2, and the beaters 9, the operating wheel adapted to rotate these beaters in a manner well understood by those skilled in the art.

The usual form of the frame 1, in this type of beaters, is to have the handle integral therewith, as shown in the said Ladd patent.

45 In my present improvement I make the handle 3 of a piece of flat material, or flat-steel wire, which is not integral with the frame 1.

50 In carrying out my present construction, the upper end of the frame 1, is provided with a loop 4, extending laterally in respect to the frame 1, and preferably to the opposite side of the frame from the operating wheel 2. The handle 3 passes through this loop 4, and is shaped to fit snugly against the 55 upper end of the frame 1, and has its lower end riveted to the frame 1, as shown at 5.

The upper extremity of the handle 3 is formed into a hand-hold loop 6, by means of which the beater is supported in its proper position to operate upon the material that is being beat.

By making the handle part separate from the frame, the handle may be differently bent or shaped to suit the particular requirements of the user and applied to the frame.

1. That is to say, the stem portion of the handle may be twisted, as at 7, to cause the hand-hold 6 to stand in a direction parallel with the plane of the operating wheel 2, as shown in Figs. 1 and 2, or the stem of the handle 3 may be left untwisted, as shown in Fig. 3, whereby the hand-hold 6 is in a direction at right angles to the plane of the operating wheel 2. One of these positions suits the requirements of some operators, whereas the other position suits the requirements of other operators.

Furthermore, by reason of this construction, the upper end of the frame is made of double thickness to give it strength and stability at the very position strength and rigidity is required. It produces a frame and a handle which is very rigid and strong and produces a handle that is readily and cheaply manufactured with the advantages herein recited.

As here shown, the edges of the frame 1 are provided with longitudinally struck outward beads 8, between which the upper portion of the stem of the handle snugly fits and which further serves to hold the handle rigid with the frame against relative lateral movement.

This construction prevents lateral vibration of the frame of the beater, and, therefore, enables the beater to be held steady and to give a firm strong feeling in the hand of the operator, and also prevents a tendency to a wedging of the turning mechanism by reason of any twisting or vibrating of the frame in operation.

Having thus described my invention, what I claim and desire to secure by Letters Patent is:

1. A beater of the type described, comprising a frame carrying a beater mechanism, the frame having an elongated upwardly projecting portion, a handle separate from and extending longitudinally of the upwardly extending portion, the handle 105 engaging the upper end of the upwardly extending portion and being attached to the

lower end thereof to provide a rigid connection between the parts, the handle extending beyond the upwardly extending portion and carrying a hand-hold.

5 2. A beater of the type described, comprising a frame carrying an operating mechanism, the frame having an upwardly extending arm, of a separate handle extending longitudinally of the frame, the handle 10 attached to the frame at its inner end, and interlocked intermediate its ends to the upper end of the said longitudinally extending frame arm, the upper end of the handle carrying a hand-hold.

15 3. A beater of the type described, comprising a frame carrying an operating mechanism, the frame having an upwardly extending arm provided with a loop, a handle extending through the loop and having its 20 lower end attached to the frame, the handle having the hand-hold at its upper end, for the purpose described.

4. A beater of the type described, com-

prising a frame carrying an operating mechanism, the frame having an upwardly extending arm with an integral laterally extending loop, of a handle extending through the loop and having its lower end attached to the frame, the upper end of the handle provided with a hand-hold, for the purpose 25 30 described.

5. A beater of the type described, comprising a frame carrying an operating mechanism, the frame having an upwardly extending arm provided at its upper end with 35 an outwardly extending loop, a handle extending through the loop and having its lower end attached to the frame, a hand-hold at the upper end of the handle, the arm of the loop having longitudinal outwardly extending beads at opposite sides 40 and engaging the edges of the handle.

In testimony whereof I hereunto affix my signature.

LAVERN BORDWELL.
